 Industrial Patents Corporation, Chicago, Ill.,
 a corporation of Delaware

Application February 18, 1937, Serial No. 126,490

5 Claims. (Cl. 253—56)

This invention relates to a motor.

An object of the invention is to provide an improved drive means for use, for example, with a skinning knife.

5 Other objects of the invention will be apparent from the description and claims which follow.

The drive means of the present invention comprises a rotor rigidly secured to a shaft and rotatably driven by fluid pressure, such as compressed air, delivered through a series of spaced jets. By way of illustration and not by way of limitation, the drive means of the present invention is shown connected with a skinning knife comprising a pair of knife blades having serrated 15 cutting edges and slidably mounted in parallel abutting relationship for relatively opposite movements.

Reference is had to the drawing in which like characters of reference are used to designate 20 similar elements.

Figure 1 is a side view of a skinning knife provided with a drive means constructed in accordance with the present invention.

Figure 2 is a top view, partly in section, of Figure 1.

Figure 3 is an enlarged side view, partly in section, of the air outlet manifold.

Figure 4 is a sectional view taken on line 4—4 of Figure 3.

30 Figure 5 is an enlarged side view of the impeller wheel.

Figure 6 is a sectional view taken on line 6—6 of Figure 5.

The skinning knife illustrated in the drawing, 35 comprises a pair of relatively long thin knife blades 1 and 2 provided with serrated cutting edges 3 and 4 and slidably mounted in parallel abutting relationship for relatively opposite reciprocal movement. Knife blades 1 and 2 are respectively secured, as at 5 and 6, with connecting rods 7 and 8 slidably mounted for reciprocal movement in bearings 9 and 10 rigidly secured in housing 11.

45 Spaced arms 12 and 13 are secured to connecting rods 7 and 8, as at 14 and 15. Arms 12 and 13 are each provided with a pair of spaced roller bearings 16 engageable with radial cam surfaces 17 and 18 of cam disk 19. Cam disk 19 is rigidly secured to rotatable shaft 20 journaled in suitable antifriction bearing 21 mounted in end plate 24. End 22 of shaft 20 is extended through opening 23 of end plate 24 for mounting rotor 25. It will be seen that cam disk 19, when rotated by 50 shaft 20, serves to reciprocate connecting rods 7

and 8 and thus the knife blades 1 and 2 in a relatively opposite movement.

Rotor 25 is pinioned or otherwise secured to shaft 20 and is provided with a series of peripheral recesses 26 against which compressed air, issuing from jets 27 of manifold assembly 28, is forcibly directed to rotatably drive shaft 20 and thus the cam disk 19.

As shown in Figures 5 and 6, the mouth 29 of each of the recesses 26 is tapered inwardly to a 10 narrow throat 30 having a closed bottom 31. Such a construction provides greater impact of the air directed against recesses 26 and thus increased power to rotor 25.

As shown in Figures 3 and 4, manifold assembly 15 28 comprises a series of tubes 32 secured at one end, as by bolts 33, to end plate 24 and cooperatively connected at their opposite end with tubular ring 34. Tubes 32 are circularly arranged in spaced relation around the periphery of rotor 20 25 and are each provided with an outlet 27, hereinbefore mentioned, for directing compressed air against recesses 26 of rotor 25.

Compressed air, from a source of supply not shown, is passed through flexible hose 35 threaded, as at 36, to valve 37 which is provided with a series of radial conduits 38 each communicating with ring 34.

It will be seen that compressed air entering ring 34 will distribute through the several tubes 30 32 and issue from jets 27 against the recesses 26 of rotor 25. The impacts of air against recesses 26 will rotate rotor 25 and thus shaft 20 and cam disk 19 whence connecting rods 7 and 8 and knife blades 1 and 2 will be reciprocated 35 in a relatively opposite movement.

It will also be seen that each of the tubes 32 and their respective jets 27 provide an individual source of power at spaced points relative to the periphery of rotor 25 thus providing a smooth 40 equilibrium and increased power to drive shaft 20. In practice, a series of eight jets has been found satisfactory.

The passage of air through valve 37 may be controlled by valve stem 39 and, as shown in Figure 1, may be operated by spring-tensioned lever 40 through connecting rod 41. Lever 40 is secured, as by spring 42, against housing 11. Lever 40 may be readily controlled by the hand of an operator by grasping the device around housing 50 11.

I claim:

1. In combination with a drive shaft, a drive means comprising a rotor provided with a plurality of peripheral recesses and rigidly secured 55

- to the shaft, and a manifold assembly comprising a series of tubes coaxially arranged in spaced relation relative to the periphery of the rotor, each of the tubes being provided with an outlet jet adapted for directing fluid under pressure against the rotor recesses and a fluid supply means connecting each of the tubes.
2. In combination with a drive shaft, a drive means comprising a rotor provided with a plurality of peripheral recesses and rigidly secured to the shaft, and a manifold assembly comprising a series of tubes coaxially arranged in spaced relation relative to the periphery of the rotor, each of the tubes being provided with an outlet
- 10 jet adapted for directing fluid under pressure against the rotor recesses, and means for uniformly supplying fluid under pressure to each of the tubes comprising a tubular ring connecting each of the tubes and in communication therewith.
- 15 3. In combination with a drive shaft, a drive means comprising a rotor provided with a plurality of peripheral recesses and rigidly secured to the shaft, and a manifold assembly comprising a series of tubes coaxially arranged in spaced relation relative to the periphery of the rotor, each of the tubes being provided with an outlet jet adapted for directing fluid under pressure against the rotor recesses, and means for uniformly supplying fluid under pressure to each of the tubes comprising a tubular ring connecting each of the tubes and in communication therewith, a fluid supply line and a series of conduits

connecting the supply line with the tubular ring.

4. In combination with a drive shaft, a drive means comprising a rotor rigidly secured to the shaft, the rotor being provided with a plurality of peripheral recesses, the rotor recesses in transverse cross section being tapered inwardly to a reduced throat and terminated in a closed bottom and a manifold assembly comprising a series of tubes coaxially arranged in spaced relation relative to the periphery of the rotor, each of the tubes being provided with an outlet jet adapted for directing fluid under pressure against the rotor recesses and a fluid supply means connecting each of the tubes.

5. In combination with a drive shaft, a drive means comprising a rotor rigidly secured to the shaft, the rotor being provided with a plurality of peripheral recesses, the rotor recesses in transverse cross section being tapered inwardly to a reduced throat and terminated in a closed bottom, and a manifold assembly comprising a series of tubes coaxially arranged in spaced relation relative to the periphery of the rotor, each of the tubes being provided with an outlet jet adapted for directing fluid under pressure against the rotor recesses, and means for uniformly supplying fluid under pressure to each of the tubes comprising a tubular ring connecting each of the tubes and in communication therewith, a fluid supply line and a series of conduits connecting the supply line with the tubular ring.

ANDREW. S. HARTANOV.
